UNITED STATES PATENT OFFICE.

JOHN D. PEDERSEN, OF JACKSON, WYOMING.

FIREARM.

Application filed April 23, 1923, Serial No. 634,101. Renewed November 2, 1925.

To all whom it may concern:

Be it known that I, JOHN D. PEDERSEN, a citizen of the United States, residing at Jackson, in the county of Lincoln and State 5 of Wyoming, have invented certain new and useful Improvements in Firearms, of which the following is a specification.

This invention relates to firearms, and is particularly concerned with the provision 10 of novel and efficient means for regulating the passage of cartridges from a cartridge storing means to cartridge conveying mechanism.

More specifically, one of the objects of my 15 invention is to provide a cartridge stop or cut-off mechanism simple in construction and reliable in operation whereby the escape of more than one cartridge at a time from the cartridge storing means to the cartridge conveying mechanism is prevented and undesirable interference with the proper functioning of said mechanism thereby avoided.

Another object is the provision of mechanism 25 wherein a cartridge stop is controlled by a member which serves as both an action bar and a cartridge transfer member. Still another object is to provide a mechanism wherein a cartridge stop is controlled by a member which serves as an action bar and also contributes to the determining of a cartridge storing space.

Other objects of my invention reside in certain arrangements and combinations of 35 parts which will become apparent as the description of my invention is hereinafter developed, and will be pointed out in the claims hereunto appended.

Referring to the drawings wherein I have 40 shown what I now consider to be the preferred form of my invention:

Fig. 1 is a fragmentary side elevation partly in section, showing my invention in connection with one type of firearm to 45 which it may be applied, the action bar and breech block being shown forward and the hammer cocked.

Fig. 2 is a view similar to Fig. 1 but showing the action bar and breech block retracted.

Fig. 3 is a vertical sectional view taken 50 on line 3—3 of Fig. 1 looking in the direction of the arrows.

Fig. 4 is a vertical sectional view similar 55 to Fig. 3, except that the cartridge stop

and action bar are shown in different positions than in Fig. 3.

Fig. 5 is a fragmentary horizontal sectional view taken on line 5—5 of Fig. 3.

Fig. 6 is a view in side elevation of the 60 rear portion of the action bar.

Fig. 7 is a fragmentary plan view showing part of the action bar.

The firearm in connection with which my invention is illustrated is in many respects 65 similar to the firearm disclosed in my Patent No. 908,883, granted Jan. 5, 1909, and, like the firearm disclosed in said patent, includes a barrel 1 secured to the barrel portion 2 of a frame or receiver, a butt stock 4 being 70 secured to the stock portion 3 of said receiver. The parts 2 and 3 of the frame or receiver enclose a chamber in which are located most of the working parts of the gun, including the breech block 5, cartridge 75 carrier 6, and hammer 7. The breech block 5 is reciprocable in the receiver and at its upper forward end is provided with an upwardly extending shoulder 8 for engaging the recoil shoulder 9 in the forward top 80 portion of the receiver. The carrier 6 is pivotally mounted on a sleeve 10 mounted in the receiver portion 3, thru which sleeve passes a screw 11 for securing together the parts 2 and 3 of the receiver. The hammer 85 7 is likewise mounted on said sleeve 10 and is adapted to be driven to firing position by a spring 12 which acts upon the head of a rod or plunger 13 connected to said hammer. A trigger 14 is pivoted at 150 in the stock portion 3 of the receiver and is spring-urged to a position for holding the hammer cocked. The parts above described being 90 similar to the corresponding parts disclosed in my prior Patent No. 908,883, above referred to, no detailed description thereof 95 is necessary.

A stationary magazine tube 15 is shown beneath the barrel, said magazine tube being mounted at its rear end in the receiver and near its forward end in a clamp 16 supported by the barrel. Within the magazine 15 is the usual follower 17 which is constantly urged rearwardly by a spring 18.

Mounted for slidable movement with respect to the magazine 15 is the action bar 19 which action bar is shown provided with a forwardly projecting tongue 20 adapted to be received between the forearm 21 and a sleeve 22 slidably mounted on the magazine 105 110.

15. The forearm, sleeve, and action bar may be secured together by a screw 23. As in my above referred to Patent No. 908,883, the rear portion of the action bar is provided 5 with a shoulder 24 and an inclined face 25 adapted to co-operate with a downwardly extending inclined projection 26 from the breech block 5, whereby the breech block may be moved into and out of its closed or 10 "breeched-up" position (Fig. 1) by movement of the action bar, as fully described in said patent.

Like the action bar shown in my patent above-referred to, the action bar disclosed 15 herein is provided in its rear portion with shoulders 30 and with guideways 27 (Fig. 7) for the rim of a cartridge and is suitably slotted as shown at 28 to accommodate the carrier 6. Any suitable means, such as 20 a spring catch 29 shown mounted on the rear part of the action bar and projecting thru the wall thereof, may be employed for gripping the rim of a cartridge abutting against the shoulders 30. As shown in Fig. 25 1, when the action bar is in its forward or home position the rearmost cartridge in the magazine 15 abuts against the shoulders 30 and the rim of the said cartridge is at the same time gripped by the catch 29. When 30 the action bar is then drawn rearwardly the cartridge aforesaid is carried rearwardly with the action bar, into the position shown in Fig. 2, wherein said cartridge overlies the carrier 6. Upon then moving the action 35 bar forwardly the carrier is raised by the co-action of a dog 31, carried by the action bar, with an inclined slot 32 in the carrier, whereby the cartridge is raised by said carrier into engagement with guideways on the face of the breech block so that the latter in moving to "breeched-up" 40 or closed position will insert the cartridge into the barrel. The co-action of the carrier dog 31 with the cartridge carrier 6 is 45 similar to that disclosed in my patent above-referred to, said dog being carried by a leaf spring 33 attached to the action bar and being cammed laterally by the inclined bottom of a cut 34 in the carrier during 50 the initial portion of the rearward movement of the action bar whereby said dog rides along the side of the carrier during further rearward movement of said action bar until at the end of said rearward movement 55 said dog snaps into the slot 32.

Inasmuch as the action bar, in addition to operating the breech block and cartridge carrier, also carries cartridges from the magazine tube to said carrier, said action bar may be appropriately termed a "combined action bar and cartridge transfer member."

It should also be noted that the action bar co-operates with the magazine tube to 65 define a cartridge storage space, the rear

portion of said action bar serving to receive at least a portion of the rearmost cartridge in the magazine when said action bar is in forward or home position, as shown in Fig. 1. Thus both the action bar and the magazine contribute to the determining of the space for storing cartridges that are to be fed to the cartridge carrier.

In order to regulate the passage of cartridges from the magazine 15 I provide a 70 cartridge stop or cut-off 35 which is shown pivotally mounted at 35' in the receiver and is provided at its upper end with a beveled nose 36 adapted to project into the path of cartridges in the magazine. Said cartridge stop is also provided with a toe 37 at its lower end, which toe is adapted to co-act with a groove 38 in the adjacent side of the action bar. When the action bar is in forward or home position as shown in 85 Fig. 1 the groove 38 is opposite the toe 37 of the cartridge stop so that the latter may be moved out of cartridge stopping position and a cartridge in contact with the nose 37 at such time will, under the influence of the 90 spring-pressed follower 17, rock said stop out of stopping position (see Fig. 3) and pass rearwardly until said cartridge abuts the shoulders 30 of the action bar. The groove 38 is provided with a beveled or inclined portion 38' so that when the action bar is moved rearwardly said inclined portion 38' cams the toe 37 outwardly and forces the nose 36 into the path of the cartridge immediately preceding the rearmost cartridge. 95 As rearward movement of the action bar continues the side of the latter comes opposite the toe 37 so that when the cartridge immediately preceding the rearmost cartridge strikes nose 36 the cartridge stop can not be rocked and further rearward movement of all cartridges forward of the rearmost cartridge is prevented. Thus movement of more than one cartridge at a time 100 from the magazine is prevented and ob-jectionable interference with the operation of the mechanism for conveying cartridges 110 from the magazine to the barrel is thereby avoided.

For limiting the movement of the action 115 bar various means may be employed. I have, for purposes of illustration, shown a projection 39, which, in co-operation with the sleeve 22 limits rearward movement of the action bar, while forward movement of said action bar is limited by a shoulder 40 in the receiver.

It will be understood that, while I have shown my improved cartridge stop mechanism applied to a certain type of gun, said mechanism is not limited to any particular type of firearm but is capable of application to a wide variety of guns. Also it is apparent that the specific structure herein disclosed may be modified and varied in nu- 120 125 130

merous ways without departing from the spirit of my invention.

Having described my invention what I claim and desire to secure by Letters Patent 5 is:

1. In a firearm, a breech block, cartridge storing means, a carrier for delivering a cartridge to said breech block, means for transferring a cartridge from said cartridge 10 storing means to said carrier, and pivoted means controlled by said transferring means for regulating the passage of cartridges from said storing means.

2. In a firearm, the combination of cartridge 15 storing means, a combined action bar and cartridge transfer member, and pivoted means controlled by said member for regulating the passage of cartridges from said storing means.

20 3. In a firearm, the combination of cartridge storing means, a combined action bar and cartridge transfer member, means in said storing means for urging cartridges from said storing means, a cartridge stop movable into the path of cartridges in said 25 storing means and means whereby rearward movement of said combined action bar and cartridge transfer member moves said stop into cartridge stopping position and whereby 30 when said member is in its forward position said stop may be moved out of cartridge stopping position by the action of said urging means through the medium of the cartridge bearing against said stop.

35 4. In a firearm, the combination of a magazine, a follower spring in said magazine, a cartridge stop pivotally mounted adjacent said magazine having a beveled nose projectible into the path of cartridges in said 40 magazine, a combined action bar and cartridge transfer member, and means for rocking said stop and projecting said nose into the path of cartridges in said

magazine when said member is moved rearwardly and for freeing said stop when said 45 member is in its forward position whereby under the influence of said follower spring a cartridge bearing against said nose may move the latter out of cartridge stopping 50 position.

5. In a firearm, the combination with a pivoted cartridge stop, of a combined action bar and cartridge transfer member for controlling said stop.

6. In a firearm, the combination of a cartridge stop, a combined action bar and cartridge transfer member, and means for moving said stop into cartridge stopping position when said member is in one position and for releasing said stop and permitting 60 a cartridge to pass thereby when said member is in another position.

7. In a firearm, the combination of a cartridge stop, a combined action bar and cartridge transfer member, a follower spring, 65 and means on said member for moving said stop into cartridge stopping position when said member is moved rearwardly and for releasing said stop and permitting a cartridge to pass thereby under the influence 70 of said follower spring when said member is in its forward position.

8. In a firearm, the combination of a cartridge stop, a combined action bar and cartridge transfer member, a follower spring, 75 and means for moving said stop into cartridge stopping position when said member is moved rearwardly and for releasing said stop and permitting a cartridge to pass 80 thereby under the influence of said follower spring when said member is in its forward position.

In witness whereof I have signed my name hereto this 20 day of April, 1923.

JOHN D. PEDERSEN.
